UNITED STATES PATENT OFFICE.

WILLIAM PARKS, OF FRAZEYSBURG, OHIO, ASSIGNOR OF ONE-HALF TO
GEORGE W. HOLTZ, OF FRAZEYSBURG, OHIO.

BAG-FASTENER.

SPECIFICATION forming part of Letters Patent No. 739,919, dated September 29, 1903.

Application filed March 18, 1903. Serial No. 148,392. (No model.)

To all whom it may concern:

Be it known that I, WILLIAM PARKS, a citizen of the United States, residing at Frazeysburg, in the county of Muskingum and State 5 of Ohio, have invented a new and useful Bag-Fastener, of which the following is a specification.

My invention relates to fastening means for bags, sacks, packages, or the like wherein is 10 employed an encircling flexible member or band; and the object of the same is to produce a device comprising a member carried by the flexible encircling member or band and a coöperating locking member movable 15 toward and away from the encircling band in a direction transversely to the strain thereof, the locking and flexible members being each provided with outer engaging portions.

A further object is to provide means for 20 holding the members into positive engagement with each other to prevent accidental displacement of the same.

To these ends my invention consists in the 25 novel construction and arrangement of the several parts of a bag-fastener, as hereinafter more fully described and claimed and as illustrated in the accompanying drawings, in which I have illustrated my preferred form only.

30 Similar numerals designate like parts throughout the several views.

Figure 1 is a perspective view of the device applied to a bag; Fig. 2, a perspective view of the fastener. Fig. 3 is a horizontal section, and Fig. 4 a detail perspective view, of the locking member.

Referring more particularly to the drawings, the numeral 1 designates a flexible member or encircling band, which may be of any 40 suitable material; but I have preferably illustrated the same as being a strap which is adapted to surround the article to be fastened. For the purpose of illustration I have shown the same as being applied to the mouth of a 45 sack or bag 2 for closing the same.

The numeral 3 designates a plate or member carried by one end of the band 1 and may be secured thereto in any desired manner, such as by rivets 4 or any other fastening 50 means. Secured to the member or plate 3 and disposed at a substantially right angle

thereto is a loop or eye 5 of any desired size and shape, and 6 designates a locking member adapted to be moved toward and away from the plate or member 3. Said plate or 55 locking member 6 is provided with apertures or openings 7, through which the legs or sides of the loop or eye 5 pass to allow the said locking member to move toward and away from the member 3 and to prevent longitudinal movement of the same. Secured to the lower face of the locking member 6 is a projection or rib 8, and 9 designates an upwardly-projecting portion or ear, preferably disposed in a parallel relation to the eye or loop 5, and 65 said projection is provided near its upper extremity with an aperture or opening 10 for a purpose to be hereinafter set forth. Secured to the band 1 at any desired point intermediate of its ends and remote from the 70 member 3 is a plate 11, which is provided with any desired number of projections or ribs 12. These projections may be formed on the plate 11 in any desired manner; but I have preferably shown them as being stamped 75 or bent up from the body portion.

Having thus fully described the construction of my invention, the operation of the same is as follows: The band or member 1 is placed around the article to be fastened. If 80 the article is a bag, the member 3 may, if desired, be first fastened thereto by means of the apertures 13, although this is not necessary. The locking member 6 is then raised as far as possible toward the top of the eye 85 or loop 5. The free end of the band or flexible member 1 is then passed beneath the locking member 6, and tension is exerted until the band tightly surrounds the article, the plate 11 being so arranged that when the proper 90 strain has been produced it will stand beneath the locking member 6. This member 6 is then forced down until the rib 8 contacts with the plate 11 the aperture or opening 10 will 95 stand just below the top of the eye or loop 5, 100 and the shackle 14 of an ordinary padlock 15 is then passed through the opening 10 and

beneath the top of the loop or eye 5 and locked. It will be seen that with this construction the shackle of the lock prevents any transverse movement of the locking member 6, thereby positively holding the encircling band 1 from slipping, and the legs or sides of the eye or loop 5 prevent any longitudinal movement of the said locking member. Obviously this construction may be somewhat changed without departing from the spirit of my invention, and, if desired, an ordinary seal or other locking means may be used in place of the padlock.

In order to insure and facilitate the easy insertion of the flexible member or band 1 between the locking member 6 and the member 3, I have illustrated the edges of the said locking member 6 as being slightly turned upward, as at 16.

20 What I claim as new, and desire to secure by Letters Patent, is—

1. The combination with a tie or band, of a fastening device having jaws between which the tie or band is interposed, and one of which is movable toward and from the other in a direction transverse to the line of strain applied to the tie or band, said band and one of the jaws being flat and the other having interlocking projections, and means for securing 25 the jaws in a fixed relative position.

2. The combination with a tie or band, of a fastening device having jaws between which the tie or band is interposed and one of which is movable toward and from the other in a direction transverse to the line of strain applied to the tie or band, the movable jaw being provided with projections and the tie or band having a plate attached thereto and provided with projections adapted to engage with the 35 projections on the movable jaw, and means for securing the jaws in fixed relative position.

3. A device of the class described comprising an encircling member, and a transversely-movable locking member carried by one end 45 thereof, the free end of the encircling member and the locking member, each being provided with interengaging projections, and means for holding the said portions in contact with each other.

4. A device of the class described, compris-

ing an encircling member, an eye carried by one end thereof, a locking member engaging said eye and movable transversely to the strain of the encircling member, interengaging portions carried by the encircling and 55 locking members, and means engaging the eye and locking member for holding the interengaging portions in contact with each other.

5. A device of the class described comprising an encircling member, an eye carried by one end thereof, a locking member movable on said eye in a direction transverse to the strain of the encircling member, interengaging portions carried by the encircling and 65 locking members, an eye carried by the locking member, and means for engaging the said eyes to hold the interengaging portions in contact with each other.

6. A device of the class described comprising an encircling member, a guide carried by one end thereof and disposed at a substantially right angle thereto, a locking member movable on said guide, an ear carried by the locking member, substantially parallel to the 70 guide, said ear being provided with an aperture, interengaging portions carried by the locking and encircling members, and means engaging the guide and ear for holding the interengaging portions in position.

7. The combination with a bag, a plate secured thereto, an encircling member secured to said plate, and a guide carried by the plate, of a locking member movable on said guide in a direction transverse to the strain of the 75 encircling member, an eye carried by the locking member, said encircling member being adapted to be clamped between the plate and locking member, means engaging the eye and guide for holding the parts into positive engagement, and means for preventing the longitudinal displacement of the locking and encircling members.

In testimony that I claim the foregoing as my own I have hereto affixed my signature in 80 the presence of two witnesses.

WILLIAM PARKS.
